CLAIM

The ornamental design for container closure, as shown and described.

DESCRIPTION

FIG. 1 is a perspective view of the container closure embodying the new design in a closed position;
 FIG. 2 is a right side view thereof, the left side view being a mirror image thereof;
 FIG. 3 is a front view thereof;
 FIG. 4 is a rear view thereof;
 FIG. 5 is a top view thereof;
 FIG. 6 is a bottom view thereof;
 FIG. 7 is a perspective view of the container closure embodying the new design in a open position;
 FIG. 8 is a right side view thereof, the left side being a mirror image thereof;
 FIG. 9 is a front view thereof;
 FIG. 10 is a rear view thereof;
 FIG. 11 is a top view thereof; and,
 FIG. 12 is a bottom view thereof.
 FIGS. 1-12 show features of a container closure in phantom lines. These features are shown for environmental purposes and do not form any part of the claimed design. Further, the phantom lines immediately adjacent the solid-line portions of the design form the boundary of the design, with the phantom lines forming no part of the claimed design.
